UNITED STATES PATENT OFFICE.

GEORGES GRENIER, OF ST. CLAUDE, FRANCE.

TOBACCO PIPE.

Application filed February 8, 1926, Serial No. 86,887, and in France December 11, 1925.

This invention has for its object an improvement in tobacco-pipes in general.

This improvement is characterized by the application in the shank of the tobacco pipe of an apertured tube presenting, at the rear of the bowl of this pipe, an obturating flange, towards the middle of its length, a central separating partition and, on the side of the mouth-piece, an outer shoulder and a screw-threaded sleeve screwing in this mouth-piece.

The end of the tube, on the side of the pipe bowl, enters in the bottom of this bowl, the flange closes a nicotine reservoir surrounding the tube, the partition separates the two parts of the apertured tube, whilst the screw-threaded portion renders this tube rigid with the mouth-piece.

The smoke from the bowl enters the tube through the corresponding apertures, passes in this tube under the flange, issues through other apertures for entering the nicotine reservoir and passing over the partition of this tube, passes again in the same tube through the apertures and enters in the mouth of the smoker through the mouth-piece.

The advantages of this system are the following:

1°: Dry tobacco owing to its absolute isolation from any moisture coming from smoker's mouth, this isolation being obtained owing to the flange and to the central partition forming an obstruction to any salivation.

2°: Perfect drawing owing to wide apertures formed in the tube.

3°: Fresh and sweet smoke owing to the circulation of the smoke and to its condensation in the nicotine reservoir which surrounds it.

4°: Nonjuicy pipe, as the bottom of the bowl is sheltered from any salivation.

5°: Absolutely unobstructable pipe owing to the perfect construction of the system.

6°: Automatic cleaning of the nicotine reservoir by the simple removal of the mouth-piece, owing to the flange which scrapes this reservoir.

By way of example, this invention will be described hereinafter with reference to the accompanying drawing in which:

Fig. 1 shows in longitudinal section the tube permitting the realization of this invention.

Fig. 2 is a cross section of the same tube made according to line A—A of Fig. 1.

Fig. 3 shows the said tube in use.

As illustrated in the drawing, the tube *a* of this invention is apertured as a lantern. Moreover, it is provided with a flange *a*¹, 60 a central separating partition *a*² and an outer shoulder *a*³ in front of a screw-threaded portion *a*⁴.

The first apertures *a*⁵ of the tube correspond to the bowl *b* of the pipe and enter in 65 the bottom of this bowl; the flange *a*¹ closes the nicotine reservoir *c* provided in the shank of the pipe concentrically with the tube; the shoulder *a*³ bears against the edge of the mouth-piece *d* and the screw-threaded 70 portion *a*⁴ of the tube is screwed in the mouth-piece, so that the tube *a* and the mouth-piece *d* are thus rendered rigid together.

The suction of the smoke is effected in the 75 bottom of the bowl *b* through the first corresponding apertures *a*⁵ of the tube *a*. This smoke goes through the tube by passing under the obturating flange *a*¹, issues through the middle apertures *a*⁶, passes in 80 the nicotine reservoir *c*, escapes from this reservoir by passing over the obturating partition *a*² of the tube, comes back in the tube by passing through the last apertures *a*⁷ and finally circulates in the sleeve *a*⁴ of the tube 85 *a* and in the mouth-piece *d* for entering the mouth of the smoker, as shown by the arrows.

During its passage in the nicotine reservoir *c* the smoke is purified and cooled. 90

By removing the mouth-piece *d*, the tube *a* is withdrawn with the latter and the flange *a*¹ of this tube scrapes all the impurities contained in the nicotine reservoir *c*, impurities which are from this fact evacuated outside. 95

The central tube *a* is preferably made of duralumin so as to be non-oxidizable, but it might be also made of bone, ebonite, etc.

It will be fitted in any manner whatever to the mouth-piece of the pipe, this mouth-piece might also have any shape. 100

The suction apertures can be replaced by a variable number of holes and the end of the tube in the bottom of the bowl *b* might be of any arrangement and have any suitable shape for ensuring the suction. 105

I claim:

A tobacco pipe comprising a bowl, a shank having a bore of equal diameter throughout, a mouth piece secured in the shank and a tube in the shank and extending into the bowl in engagement with the wall 110

thereof, said tube having its outer end screw threaded and screwing into the mouth piece, a shoulder abutting against the mouth piece, a partition spaced from the shoulder, and a flange spaced from the partition and the inner end of the tube, said flange lying in the bore of the shank at its entrance into the bowl and closing communication between

the bowl and shank, the tube being provided with longitudinal slots between the shoulder and partition, the partition and flange and the flange and the end of the tube. 10

The foregoing specification of my "improvement in tobacco pipes" signed by me this 19 day of January, 1926.

GEORGES GRENIER.
